UNITED STATES PATENT OFFICE.

BENJAMIN B. BLACKWELL, OF JAMAICA, NEW YORK.

IMPROVEMENT IN PRINTERS' FURNITURE.

Specification forming part of Letters Patent No. 118,425, dated August 29, 1871.

To all whom it may concern:

Be it known that I, BENJAMIN B. BLACKWELL, of Jamaica, Queens county, in the State of New York, have invented a new and useful Improvement in Means for Holding Stereotype and Electrotype Plates for Printing in Newspaper Columns; and I hereby declare that the following is a full, clear, and exact description of the same, reference being had to the accompanying drawing which forms part of this specification.

My invention consists in the combination of a flanged holding-plate, (one or more,) an ordinary column-rule, (one or more,) a stereotype or electrotype plate, and a block or bed upon which to transiently rest such stereotype or electrotype plate, whereby, in the printing of newspapers from unblocked stereotype or electrotype plates, a great saving in the printer's furniture or paraphernalia necessary in such cases is effected.

In the accompanying drawing, Figure 1 is a face view of a printer's form wherein stereotype plates are held to their blocks by means of my improved holding-plates. Fig. 2 is a transverse section of the same. Fig. 3 is an enlargement of a portion of Fig. 2.

A A designate the beds or blocks upon which the stereotype plates B B rest and are supported. C C are the holding-plates or rules, which I term flanged holding-plates. The upper edges *a* of these plates are bent over at an angle, so that when one side is placed against the block upon which the stereotype plate rests said deflected edge or flange will enter V-shaped grooves *b* in the edges of said stereotype plates, as shown in Fig. 2, or will overlap downwardly-beveled edges of such plates. I prefer, however, to provide the side edges of the stereotype plates with grooves *b*, because this construction admits of the impression-surfaces of adjacent plates being brought close together. D D represent column-rules of the ordinary construction, one of which is placed between two holding-plates, C C, the same as it would be between two columns of type or up against the right and left-hand holding-plates in a form where outside column-rules for the page are desired.

I am aware of the fact that in a pending application (filed by A. J. H. Duganne) for a patent there is described a column-rule which is pro-

vided with grooves in its sides, into which are slid the stereotype plates, and I will here remark that such a rule must necessarily be made quite thick in order to admit of sufficiently deep grooves being made in it on exactly opposite sides to receive the edges of adjacent stereotype plates; and further than this, where such rule is used it becomes impossible to leave more than a certain positive blank space upon the paper, between the printing and the column-rule line, whereas with my invention justifying column-strips may be crowded in between the holding-plates C C and column-rule D, and hence permit adjusting for different widths of columns to any extent desired; and furthermore, when it is desired to use heavy or full-faced column-rules, as in the case of the death of a prominent person, my invention permits the ordinary rules being withdrawn and removed, or full-faced ones being quickly slid in between the holding-plates C. This cannot be accomplished where the grooved column-rules are used without removing such rules as are adapted for ordinary use and substituting in their places the same style of rules specially constructed with a full or broad face for the purpose. And besides all this, my improved holding-plates enable the publisher to still use the ordinary column-rules in his possession and previously in use in his paper, and the cost of my improved holding-plates is merely nominal as compared with the grooved column-rules.

It will, therefore, be seen that I effect the desired result—that of holding loose or unblocked stereotype plates to their blocks or beds by means of flanged holding-plates, the flanged or deflected parts of which either enter grooves in the edges of the stereotype plates or overlap beveled edges of said plates—and I employ the ordinary column-rule for imprinting the column-lines on the paper. This is quite the reverse of the operation of the grooved column-rules above referred to; there the edges of the stereotype plate slide in a groove in the rule, and the rule is provided with a column-line impression-edge.

And I accomplish many advantages by my invention; for instance, a great saving in the first cost of the devices and a simplifying of such devices; the column-width-adjusting feature; the quick changing of column-rules with one style

of face to those with another style of face; greater facility in adjusting the devices so that they will remain in true position during the locking-up operation.

What I claim as my invention, and desire to secure by Letters Patent, is—

The combination of a flanged holding-plate with

an ordinary column-rule, a loose stereotype or electrotype plate, and its block or bed, substantially as and for the purposes herein specified.

BENJAMIN B. BLACKWELL.
